HIGH GAIN AMPLIFIER

Orrin Weston Pineo, Milo, Maine, assignor to
American Cyanamid Company, New York, N. Y.,
a corporation of Maine

Application May 2, 1942, Serial No. 441,457

7 Claims. (Cl. 250—41.5)

My invention relates to high gain amplifiers and particularly to the amplifiers used in conjunction with flickering beam spectrophotometers where the amplifier input signal is supplied by some converter of radiant energy into electric energy such as a photocell, bolometer, thermocouple, or the like.

One of the most serious problems in the high gain amplifiers used to amplify the A. C. component of photocell current in flickering beam spectrophotometers of the type described for example in my earlier Patent 2,107,836 is to eliminate spurious signals, because the proper signal is vanishingly small at balance of the photometer. In general, input signals of the order of 1 microvolt are large enough to drive the photometer nearer to balance, while smaller signals are lost below the level of unavoidable thermionic "noise." Stray signals much larger than this amount can be caused by currents flowing through the capacities between the transformers and their cases, the motors and their frames, and the like. It is the object of my invention to eliminate, by means of suitable grounding connections, these stray signals which otherwise would cause the photometer to deviate appreciably from true balance.

It is customary where it is desired to avoid the effects of capacities to shields and currents flowing in shields, to ground all points which are to be grounded by separate wires to a single point. This is common practice where shielding must be extremely effective as for example, in radio signal generators where it is necessary to prevent radiation so that the only signal reaching the outside passes through the generator output wires. When, however, this standard practice is employed in the high gain amplifiers considered here, serious difficulties have arisen; amplifiers have been so constructed and have been operated, but their sensitivity, stability, and reliability have left much to be desired. Difficulties involved in these constructions used in the past have necessitated separate shielding of the photocell which makes it impossible to put the photocell actually in the photometric integrating sphere. This results in a serious loss in sensitivity because the photocell outside the sphere does not receive as large a portion of integrated light as is possible when it is actually placed inside the sphere.

According to the present invention the stray capacities in the input circuit of the amplifier are shunted out by a low resistance conductor which carries a minimum of current and which is sep-

arate from the ground wires carrying much larger currents from other portions of the instrument. In other words, the present invention adopts exactly the opposite procedure from that which is normally used where maximum shielding is desired.

The invention will be described more in detail in conjunction with the drawing which shows a diagram of a high gain amplifier with photocell input and associated apparatus used in a flickering beam spectrophotometer of the type described in my Patent 2,107,836, above referred to.

While the flickering beam spectrophotometers constitute the most important type of instrument in which amplifiers of the present invention are to be used, it should be understood that they are not limited to this use.

In the drawing the frame of the spectrophotometer itself is shown diagrammatically at 1. On this frame is mounted a balance motor 2 and part of the frame forms an integrating sphere 3 in which or immediately below an opening in which is found the photocell shown at 4. The cathode of the photocell is connected directly to the control grid of a pentode vacuum tube 5 forming the first stage of the high gain amplifier. The plate of the amplifier is fed from the source of positive direct current B+ through a high resistance 12 and the load resistance 13, while the screen grid is fed through the same resistance 12 and another resistance 14. A suitable filter condenser 20 leads from 12 to the low side of the D. C. supply voltage B-. A second condenser 21 by-passes alternating current from the screen grid of tube 5 to the cathode 6 of the same tube to which the suppressor grid is connected in the conventional way. Operating potential for the photocell anode is conveniently taken from the screen grid of the same tube.

The rest of the amplifier is divided into stages marked S₂, S₃, S₄ and S₅, this portion of the circuit being conventional. The grid of the second stage S₂ is fed from the plate of tube 5 through the small condenser 15. The early stages of the amplifier are shielded by a shield 8 to which the cathode 6 of tube 5 is connected through conductor 9. The grid circuit of tube 5 has equivalent resistance R_g and capacitance C_g as shown in dotted lines.

With the photocell cathode directly coupled to the grid, as just described, they assume a "floating potential" at which the electron stream from the photocell cathode is equalled by a portion of the tube electron stream which is intercepted by the grid. Other paths for the electrons, such as

leakage paths, are made negligible by careful insulation. Thus a whiter sample gives more D. C. photocell current and the grid floats at a higher potential where it will attract more electrons from the tube stream. At the same time, the space charge between grid and cathode becomes less and the consequent tendency for the tube current to increase is offset by a lowering of the screen voltage to maintain constant current drain from the supply through the high resistance 12. The lower screen voltage keeps the grid resistance from going down at the higher grid potential. This action is all by way of adjustment to different D. C. photocell currents. The A. C. photocell current flows through the imped-

$$\frac{R_g}{1 + R_g \cdot \omega C_g}$$

to give the input signal. Direct coupling of the cathode of the photocell to the control grid of the first stage tube is not new in photocell fed amplifiers. In fact, it has been used in a commercial spectrophotometer which is widely used and which is sold by the General Electric Company and described in my U. S. Patent 2,107,836 above referred to. In the General Electric amplifier, however, the screen grid potential is kept constant by means of a separate battery. This results in a wide variation in the resistive component R_g of the grid input impedance with variation of the D. C. photocell current. Since these variations in a practical spectrophotometer amount to about 1,000 to 1, at some point in the range the resistive component R_g becomes equal to the capacitive component $1/\omega C_g$ and at this point there is an abrupt change of phase in the first stage output signal amounting to 90° . This causes serious difficulties in a spectrophotometer because the amplified signal and the field currents in the balance motor of flickering beam spectrophotometers should have a phase relationship of 0° or 180° .

A more serious difficulty is encountered in the effect of the stray capacity between the photocell and the frame 3. This is shown on the drawing in dotted lines as an equivalent condenser 26 whose capacity is comparable with the total input capacity C_g of about 10 micromicrofarads. Therefore an A. C. voltage at the signal frequency of the amplifier, normally 60 cycles, which may appear between the frame 3 and the first stage cathode 6 will cause a stray input signal. According to the present invention this is avoided by directly connecting the cathode 6 to the frame of the integrating sphere 3 by a heavy conductor 1 which may, for example, be about 4 ft. of No. 18 copper wire. The largest 60 cycle current allowed to flow in this wire should be smaller than 40 microamperes, if the IR drop in the wire is to be less than the one microvolt mentioned above.

The frame 1 and the integrating sphere 3 are connected to ground through a conductor 19 and others. It will be apparent, therefore, that instead of connecting cathode 6 to ground as directly as possible and to the same point as all the other parts of the system which are to be grounded, its connection to ground is through conductor 19. This is important because the A. C. currents flowing from the frame to ground, for instance as a result of capacity 29 between the winding and the frame of motor 2, will be much larger than can be tolerated through 1 or any other wire in the path from 6 to 3. These

currents may amount to several hundred microamperes.

By this arrangement, the only voltage across the stray capacity 26 is the voltage drop in conductor 7 due to currents which must pass through the high plate load resistance 13 and the higher internal plate resistance of the tube. The gain in the first stage is around 20 times, and the ratio of plate resistance to load is at least 5, so that more than 100 times as much stray voltage can be tolerated between the first and second stage ground points, 6 and 15 respectively, than can be tolerated between the ends of conductor 7. Thus the first stage is effectively isolated from the rest of the amplifier and is tied to the photocell surroundings.

The B- lead is connected by 17 to the power amplifier chassis 11 at a point 16 between S_3 in the voltage amplifier and S_4 in the power amplifier. It is convenient to have this connection in the power amplifier so that the latter is properly grounded even when the voltage amplifier plug connector is opened. Also if the point 16 were closer to the end 15 of the cathode resistor of stage 2, the current through the stray capacity 27 between the power transformer and its case might cause pick-up due to the IR drop in the B- lead between stages S_2 and S_3 ; and if 16 were closer to the rectifier, the signal currents in the lead between 15 and 16 might give enough voltage between 6 and 15 to cause oscillation. Besides that in lead 7 which is negligible, the other voltages appearing between 6 and 15 are the drops in leads 17, 18 and 19. Lead 17 carries the stray current through the capacity 27, lead 18 carries the stray current through capacity 28, and lead 19 carries the stray current through the capacity 29. In the amplifier of the present invention, leads 17 and 18 are reduced so that they have practically no resistance at all and lead 19 is of No. 16 wire and only about a foot long. It should be noted that lead 17 connects to frame 3 at a point outside the path from the stray capacity 29 to the lead 19.

The present invention has been described in conjunction with an amplifier for a visible light using flickering beam spectrophotometer as this is of course the most important and widely used spectral region. The same difficulties are encountered, however, in spectrophotometer using the near ultraviolet or near infrared as in those using visible light and the present invention can be utilized therefor. Likewise it is adaptable with devices operating further into the infrared but in such cases other types of radiant energy converters such as bolometers or thermocouples are used in place of the photocell. Accordingly it should be understood that the present invention is generally applicable to flickering beam spectrophotometers regardless of whether they are operating in the visible spectrum using a photocell as the transformer, or in other parts of the spectrum using other types of transformers of radiant energy into electrical energy.

What I claim is:

1. A high gain, multi-stage vacuum tube amplifier having a screen grid vacuum tube in the first stage fed by a transformer into electrical current of radiant energy of frequency higher than radio waves, comprising a transformer of said high frequency radiation into electric current surrounded by a grounded electric frame, the output terminals of said transformer being connected directly to the control and screen grids of a screen grid vacuum tube of the first

stage of the amplifier, the connection being in a direction such that increase in steady input of radiant energy to the transformer will result in impressing a voltage differential between the control grid and screen grid such that the latter becomes relatively more positive with respect to the control grid, means for directly grounding the cathode of the said vacuum tube to the metallic frame surrounding the energy transformer through a low resistivity conductor, a source of high D. C. potential feeding the anode of the screen vacuum tube and a high resistance connecting said source of D. C. potential to the screen grid of the vacuum tube, said resistance constituting the only conducting path between the screen grid of the vacuum tube of other portions of the amplifier.

2. A high gain multi-stage vacuum tube amplifier having a screen grid vacuum tube in the first stage fed from the output of a phototube, comprising a phototube surrounded by a grounded metallic frame, the anode being directly connected to the screen grid of the screen grid vacuum tube of the first stage of the said amplifier, the cathode of the said tube being directly connected to the control grid of said vacuum tube and having no other conductive connection, a source of high D. C. potential feeding the anode of the vacuum tube and a high resistor connecting said D. C. potential source to the screen grid of the vacuum tube and constituting the only conductive path from said grid to any element of the amplifier, the cathode of the vacuum tube being directly connected to the metallic frame through a low resistance conductor.

3. A high gain multi-stage vacuum tube amplifier having a screen grid vacuum tube in the first stage fed by a transformer into electrical current of radiant energy of frequency higher than radio waves, comprising a transformer of said high frequency radio in electric current surrounded by a grounded electric frame, the output terminals of said transformer being connected directly to the control and screen grids of the screen grid vacuum tube of the first stage of the amplifier, the connection being in a direction such that increase in steady input of radiant energy to the transformer will result in impressing a voltage differential between the control grid and screen grid, causing the latter to become relatively more positive with respect to the control grid, means for directly grounding the cathode of the said vacuum tube to the metallic frame surrounding the energy transformer through a low resistance conductor, a source of high D. C. potential feeding the anode of the screen vacuum tube and a high resistance

connecting said source of D. C. potential to the screen grid of the vacuum tube, said resistance constituting the only conducting path from the screen grid of the vacuum tube of other portions of the amplifier, the cathode of the vacuum tube being ungrounded except through said low resistance conductor to the metallic frame.

4. A high gain multi-stage vacuum tube amplifier fed from the output of a phototube, comprising a phototube surrounded by a grounded metallic frame, the anode being directly connected to the screen grid of the screen grid vacuum tube of the first stage of the said amplifier, the cathode of the said tube being directly connected to the control grid of said vacuum tube and having no other conductive connection, a source of high D. C. potential feeding the anode of the vacuum tube and a high resistor connecting said D. C. potential source to the screen grid of the vacuum tube and constituting the only conductive path from said grid to any element of the amplifier, the cathode of the vacuum tube being directly connected to the metallic frame through a low resistance conductor, but otherwise ungrounded.

5. An amplifier according to claim 1 in which the screen grid of the vacuum tube is connected to the cathode through a condenser presenting an impedance path at audio-frequency which is low in comparison to the resistance connecting the screen grid of the vacuum tube to the source of D. C. potential.

6. An amplifier according to claim 3 in which the screen grid of the vacuum tube is connected to the cathode through a condenser presenting an impedance path at audio-frequency which is low in comparison to the resistance connecting the screen grid of the vacuum tube to the source of D. C. potential, the early stages of the amplifier being provided with a shield insulated from the shield of the latter stages, this stage shield being connected through a low resistance conductor to the cathode of the screen grid vacuum tube, but otherwise ungrounded.

7. An amplifier according to claim 4 in which the screen grid of the vacuum tube is connected to the cathode through a conductor presenting an impedance path at audio-frequency which is low in comparison to the resistance connecting the screen grid of the vacuum tube to the source of D. C. potential, the early stages of the amplifier being provided with a shield insulated from the shield of the latter stages, this stage shield being connected through a low resistance conductor to the cathode of the screen grid vacuum tube, but otherwise ungrounded.
